(57) **CLAIM**

The ornamental design for a flying vehicle and/or toy replica thereof, as shown and described.

DESCRIPTION

FIG. 1 is a front perspective view of a flying vehicle and/or toy replica thereof showing our new design;

FIG. 2 is a front view thereof;

FIG. 3 is a right side view thereof;

FIG. 4 is a left side view thereof; and,

FIG. 5 is a top view thereof.

The broken line showing of various regions on the flying vehicle and/or toy replica thereof are for environmental purposes only and form no part of the claimed design.

1 Claim, 5 Drawing Sheets
